B. Kugler,

Wood Planing Machine.

Patented June 3, 1833.

Benjamin Ruyler Phil. Penn

Seton Patent

In witness whereof to the Seton Patent and the true intent of the same I do
-sign a description to the name of the said Benjamin Ruyler Inventor of an
Improvement called "Ruyler's planing machine."

In witness whereof I do sign this 3d day of June 1859, before the City of
Philadelphia and State of Pennsylvania doth declare.

I do swear that Benjamin Ruyler have invented and constructed and
applied to me a new and useful improvement in the method of planing timber
-by sawing and cutting into timbers either plank boards or any other
material board so reducing the same to an equal thickness viz a saw and
surface machine called "Ruyler's planing machine" specified in the words following
etc. This improvement and machine is thus described.

The pieces of timber called the timber, from twelve to fourteen inches square
and about forty feet long are to be placed horizontally and parallel to each
other about three inches apart and well secured on a solid foundation (Pl. 1.
fig. 1) so they are kept at the proper distance by blocks. (Pl. 1 fig. 1A, B, C, D).

On the surface of each timber and at the distance of about three inch-
es from the top is to be cut a space two inches wide and one in depth run-
ning horizontally the whole length of the timber and called the groove
(of which is more preferable) the groove or slot which may be made of
cut over or other tools and set into the timber (Pl. 1 fig. 1B, C, D).

On the top of the timber and well secured there to be placed
horizontally the holding tool of a rectangular shape open at both ends and
large enough to contain and receive of a fore-sawing for the
longest nail and thickest board intended to be planed. (Pl. 1 fig. 1E.)
Nailed to the bottom of the bottom of the holding tool (which must be thin-
-by no the eighth of the space between the timbers) there must be a longi-
-tudinal opening called the "Rock slot" about two inches wide running
the whole length of the tool to which leave a free space for the back of the tool

hereinafter described. The holding box must be long as the longest board intended to be planed and capable of being adapted by means of movable and lateral guides (A.1 Fig 1 & C. 111) to the different widths of the board in turn to be planed. The top of the holding box may be left open in which case the box must be far enough the top, and the board must close the one exactly in the box will form the top. If the top of the holding box be not left open the side must be so left in which case the box must be far enough the side. Both these modes of fastening the box are hereinafter described.

In the hinder at the front end contiguous to the holding box is placed the planing box, A.1 Fig 6 D, of a rectangular shape open at both ends, steel surface long with straight sides to receive the board, as hereinafter described and having a longitudinal opening (called the neck slot A.2 Fig 5 A) through the centre of the bottom extending the whole length of the planing box and of the same width as the neck slot in the holding box. The planing box is to be so placed that the upper surface of the bottom planing shall be in a horizontal line with the upper surface of the holding box and that the neck slots of the two boxes shall form one straight line. The bottom and sides of the planing box are thus made. Then shall be a rectangular plate of cast iron (called a bottom plate A.2 Fig 1 A) square long, one foot wide and one inch thick, perfectly flat on the under surface and having on the upper surface perpendicular thereto and exactly flat with the upper edge thereof, many rectangular blocks (called bottom blocks A.2 Fig 1 B & C) as shall be placing (with planing blocks) each four inches long by twelve long by three wide along the bottom plate three-quarters of an inch wide over the neck slot with a space or interval of one inch between each at the posterior end of the bottom plate is placed a stay (A.2 Fig 1 C) to prevent the side over top plate from moving backwards.

The bottom plates and bottom blocks and stay to be cast in one piece. This plate is to be securely fixed by screw bolts in one of the holes in such a position that the bottom blocks shall form one side of the neck slot to the planing surface in part of the upper surface of the bottom of the planing box. Another and corresponding bottom plate and blocks is to like manner to be secured in the other hinder. There must be two other rectangular plates of cast iron (called side plates A.2 Fig 1 A)

back of them, leaving a hollow with a side or side block perfectly flat on the inner surface and having on the upper surface a series of triangular blocks (called Side Blocks, A. 2 3/4, 2 3/8) as there are to be planing bolts, the back of each to be from under the long continuing lengthwise along the side plate, and the edges of each to be on the outer edge of the side plate with a square interval of four inches between the respective ends of the backs of each corresponding with the intervals between the bottom blocks. The anterior end of the base of each side block is to be at the distance of one quarter of an inch from the inner edge of the side plate, and the posterior end of the base of each side block is to be at the distance of six and one half inches from the inner edge of the side plate.

The anterior side of each side block is to be at an angle of forty five degrees with the line of the inner edge of the side plate. The first side block, A. 2 3/4, 2 3/8, the one to which is nearest to the bottom block, to be at an anterior corner of the thickness of the board which is along the plane, and the last side block is to be at its anterior corner exactly of the thickness of which the board is to be reduced by the plane. The intermediate side blocks are to be graduated between these two extremes. Each side block is to be one eighth of an inch thicker at its posterior than at its anterior corner, the upper surface of each, A. 2 3/4, 2 3/8, being formed & planed at an angle with the horizontal and fitting exactly the side surface of the top of the planing bolt, to be immediately deposited on the anterior sides of the four side blocks on each side plate, as required. Under bolts on the remaining eight side blocks, one of the side plates are required to require bolts and on the other two using bolts. Each side plate with its side blocks ought to be cast in six pieces and the castings, when mounted, are of course expected to be reduced to the necessary accuracy and smooth by the file.

When the side plates are laid upon the bottom plates the side and bottom blocks will correspond with each other respectively. The side plates are to be placed upon the bottom plates to the line of the side blocks forming the side of the planing bolt. The side plates are immovable on the bottom plates and are to be adapted to the different widths of the board to be planed they are to be placed so as to converge toward the posterior end according to the command of the gradual reduction of the width of the board and they are caused in the proper position by means passing through the last four marks so provided for sustaining down the top of the planing bolt.

The top of the Planing Box is a rectangular plate of cast iron (call it the top plate, &c. &c. Fig. 4, 5) seven feet long about sixteen inches wide and about three inches thick having longitudinal openings through the centre six feet long and as wide as the widest board intended to be planed to save expense in casting the top plates may be cast thinner between the places through which the screw bolts pass as in the Planing Fig. 6.

In this opening are placed as many triangular blocks (call them top blocks) as there are to be planing bits the bases of the top blocks are four and a quarter inches wide and as long as the opening in the top plate is wide and the outer triangular side of each top block to form an angle of forty five degrees with the base the bases of the top blocks being part of the under surface of the top plate between the ends of the bases of the respective top blocks intervals or spaces are left of one & three quarters inch on the outer sides of the top blocks and placed the cutting bits to be fastened by screws or otherwise as hereinbefore described the cutting bits may be made best, grey iron, polished or plain and set back nearly or obliquely (Fig. 2, 3, 4 & 5) the top blocks and top plates are to be cast in one piece. The under surface of the top plate is to be first filed perfectly level then from the first cutting bit (i.e. the one nearest the Planing Box) to the second made to form each cutting bit to the one next behind it the under surface of the top plate is filed at such an angle as to correspond with and exactly fit into the upper surfaces of the side blocks hereinbefore described.

The top plate rests on the upper surfaces of the side blocks and is fastened down by four large screw bolts (Fig. 2, 3, 4 & 5) one each side passing through the timber and bottom plates but, notice of the side plates do not hold all the weight of the Planing box evenly to either side of these screw bolts are however to admit screws to slide up through them horizontally and regulate exactly the position of the side plates & so to may be cast in the top plate (Fig. 2, 3, 4 & 5) a angle which the screw bolts passing through the side plates and the bottom plate the side bolts being incapable to move so as to affect the position of the side plates being altered laterally.

The cutting bits may be secured by being set in slots having a spring at the bottom to hold them up where it

is too low in the top at each side is a piece of iron (A 2 Fig 5 C) turning on a pivot and cutting in a rectangular joint as in the angle which a lever has
from the arm turned so as to lay along over the cutting bit the lever will
operate directly on the jaws and depress it to its proper place. In the upper part
of the cutting bit there are two holes into which a hook may be inserted to clear
out the bit.

10. Whirls (A 1 Fig 1 ~~12~~) are to be placed one at each end of the bridge
on which act as a friction wheel, and may be cogged. The other is attached
to the machinery frame and must be caged so as to let upon an elliptical plate
chain (A 1 Fig 1 DOD) of iron thirty nine feet in length, sprung, so the two
which are to slide are firmly fixed in or upon dogs at equal intervals.

It is better to have the dogs cast in the respective blocks of the chain so the track they
are attached to the friction wheel must be on sliding plate so as to lighten
the load on the chain. The dogs (A 1 Fig 1) are two made. The lower part called
the foot. A 1 Fig 4 is about two inches thick eighteen inches long and three inches
wide so that when laying between the blocks it will fit and run easily
in the groove. The ^{part} must be cast horizontal along the middle of the lower blocks,
so as to allow the weight of the wheel to work in the blocks of the chain under the dog.
At right angles from the centre of the foot the neck (A 1 Fig 2 & 3) about four
inches long and two inches wide so as to fit and run easily in the necks. The
neck is such a height as to be level with the upper surface of the bottom of the
holding box. The chain A 1 Fig 2 & 3 is formed at right angles in the top of the
neck being about three quarters of an inch high two inches wide and half
as much in length less than the middle of the iron intended to be planed.
The head may be square and formed in front of the neck by having a
nucleus coming down in front of the neck and turned mortise by successive
turnings. The head must be placed so that when the elliptical chain and dogs
are placed round them and the machinery set in motion, the dogs will pass
successively through the friction setting in the groove the neck passing through
the neck slot and the head in the cavity of neck just along the upper surface
of the bottom of the holding and running box (A 1 Fig 1).

The machine may be put in either of
the ways viz by the sides or by the top of the holding box in the first case

one side of the holding box is open for the reception of the board a number of
beads are placed inconveniently along sides of the opening the rest which are
left in this position by upright grooves of a suitable height (2 1/2 in.
3 in.). The uncanined forefeet of a dog (4 1/2 lbs. B.B.) are attached to the beads
(2 1/2 lbs.) which stand upon a flat board the board is to be placed that
the dog immediately on leaving the holding box shall keep the head and fore
part of a body passing round and under (2 1/2 lbs. B.B.) it assumes the position (2 1/2 lbs.)
which sets up the board to the dog so as to push it into the cavity of the
holding box usually taken by the front dog this being effected a straight wire
splicing (2 1/2 lbs.) attached to the beads causes them to fall back and the board are
then in its original position.

The better mode of holding is believed to be through the
top on which on the holding box is placed a top instead of one of the beads upright
grooves being caused by a piece straight the board to be placed are placed directly
under the cavity of the holding box. The board is to be this will fall down
on the holding box and to be taken by the dog the board next about will form
the top of the box and when the dog leaves the box will in no time fall into the
cavity thereof. The pile must always be composed of a sufficient number of
beads to keep the board raised by their vertical pressure from breaking up
so as to keep the pile upright, of course the holding box may
be full through either the top or side by hand by putting one board at a time
into it the dogs are attached & push the board through the holding and
pushing back the holding box is the purpose of holding and guiding the
board while it is pushed into and through the plane, the dog keeping it
in the true position laterally and the top and bottom following its fore and
back direction as well as preventing it from breaking or breaking while
it is pushed into and through the holding box.

The grooves and side and top plates are placed at
the interior end and the first bottom block is also placed so as to admit
easily and guide the middle chain and feet and head of the dog respectively
and the beads. The beads may attach to them on board gradually
so as to keep the pile upright, of course the holding box may
be full through either the top or side by hand by putting one board at a time
into it the dogs are attached & push the board through the holding and
pushing back the holding box is the purpose of holding and guiding the
board while it is pushed into and through the plane, the dog keeping it
in the true position laterally and the top and bottom following its fore and
back direction as well as preventing it from breaking or breaking while
it is pushed into and through the holding box.

In the planing to the desired object will reduce the board to the required thickness and width and at the same time plane tongue and groove it by taking off successive shavings each so thin as not to occasion a resistance too difficult to overcome or which may endanger the bit or other part of the machinery or require them to be made of greater strength than may be done with convenience. There can of course be no accuracy in fixing the precise thickness of each shaving, so practical to far I have found it convenient to reduce the board by planing it through the planing box one quarter of an inch in thickness and the same in width and the description given above is of a machine calculation for such a reduction. Each cutting bit therefore will take off ^{about} $\frac{1}{4}$ of an inch of an inch in thickness; each jointer bit about one thirty second of an inch in width the planing and planing bits of course make the tongue and groove nearly without returning the absolute width of the board.

The form of the planing box being horizontal while the last cutting bit is one quarter of an inch lower than the first it follows that the general inclination of the top plate is downwards from the exterior to the posterior end. If therefore the outer surface of the top plate were a plane, it would follow that the passing from each cutting bit to the next on the board would be made through a diminishing cavity not equal to its own thickness and tongue which therefore it could not pass without great friction and difficulty and being actually supported at all times in inconvenience the outer surface of the top plate is cut upwards and such as from each cutting bit to the next behind it is found upon description to that the part of the surface between every two cutting bits forms a reverse angle to the one formed with the horizontal by the general inclination of the top plate. The consequence of this and a sine in expedient applied to the side blocks is that the board passes through the planing box with the least possible friction and without troubling any part except the bottom thereof and the edges of the several bits. The wheels and outlet chain being put in motion it is evident that the first dog will act upon the side of the board in the hollow box and push it along through that side the planing box; as soon as the board has left

1605X

the holding bay machine being supplied and ready for the westing which is then about to enter the holding bay. The blade must of course operate with perfect accuracy when properly constructed and used; it is however important not to strain or over strain the risk of breaking any part of the machine. Sometimes the head of the bay may get under the end of the board the consequence of this being that it is otherwise defective in which case of the planning bay be faulted when it is evident that either the machine must stop or that some part of it must give way. It may frequently happen that a small nail will require to be more reduced in width or thickness or to the same is prepared to be done by once piping through the planning bay. It is my intention therefore first to pass the board through the machine without fastening down the top plate and without the tool being or proceeding fast and when the end of the board shall have been fastened on the board itself reduced to within one quarter of an inch of the desired width and thickness then to pass it through with the top plate fastened by screws or springs or weights and the machine arranged as hereinafter described.

The references herein are to the drawings annexed hereto. I claim as new and my original invention --

1° The mode of constructing the holding bay and the machine in which the board is therein passed from the holding or breaking to the planning bay while the force for pushing it through is applied by the bay at the end of the board.

2° The construction of the planning bay and the combination and arrangement of the tools therein and the mode in which friction is diminished by the arrangement of the tools angles at an acute angle and do not claim as new and my original invention any other part of the machine above described. In testimony that the above is a true specification of my said improvement or invention I have here set my hand and seal the twenty fifth day of May in the Year of our Lord one thousand eight hundred and thirty three.

John H. Moore
